UNITED STATES PATENT OFFICE.

JAMES PETER ROE, OF POTTSTOWN, PENNSYLVANIA.

OSCILLATING PUDDLING-FURNACE.

1,375,181.

Specification of Letters Patent. Patented Apr. 19, 1921.

Application filed March 29, 1919. Serial No. 285,991.

To all whom it may concern:

Be it known that I, JAMES P. ROE, a citizen of the United States, residing at Pottstown, in the county of Montgomery and State of Pennsylvania, have invented certain new and useful Improvements in Oscillating Puddling-Furnaces; and I do declare the following to be a full, clear, and exact description of the invention, such as will enable others skilled in the art to which it appertains to make and use the same.

The invention relates to oscillating puddling-furnaces, and particularly to the type shown in the United States Letters Patent, No. 678,281, granted to me on July 9, 1901.

The object of the invention is to provide simple and effective means to increase the speed of the oscillating puddling-furnace, at the same time economizing in power, and, likewise, to reduce the shock and strain due to the sudden starting and stopping of especially large and heavy furnaces.

In the accompanying drawings, in which like reference letters indicate corresponding parts in the two figures:

Figure 1. Is a side elevation of my improved puddling-furnace, the latter being shown in dotted lines, and,

Fig. 2. An end elevation, partly in section, of the important parts of Fig. 1.

In said drawings, *a* represents (in outlines) an oscillating furnace, and *b* its supporting columns. To each side of the furnace are secured the ends of ropes *c* (as shown at *e*), passing over sheaves *d*, *d*—to the cross head *g*, which latter is pivotally mounted on plunger *h* adapted to reciprocate in cylinder *m*, having a suitable bushing *o*.

The operation is a very simple one. When the furnace *a* is being oscillated, that is to say is being moved, in either direction from its normal position, it draws the ropes *c* with it, and as the latter, after passing over

the sheaves *d*, *d*, are secured to the cross-head *g*, the plunger *h* is moved into the cylinder *m*, thus compressing the air contained in the latter. The result of such compression is the retarding of the movement of the furnace while it approaches its limit, and by means of the increased pressure in the cylinder, stops the furnace without shock, simultaneously storing up energy for quick acceleration when starting in the opposite direction.

The initial pressure in the cylinder *m* may be that of the atmosphere, or of any higher pressure found necessary to most fully accomplish the desired result. I do not intend to limit myself to the details of construction shown, as modifications can be made without changing the scope of my invention, but what I claim as new, and desire to secure by Letters Patent, is:

1. In a device of the character described, air compressing means, an oscillating puddling furnace and separately arranged from said furnace, and means connected with the latter and with the air compressing means to control the latter and vice versa, for the purposes set forth.

2. In a device of the character described, means connected with an oscillating puddling-furnace, comprising a cylinder, a plunger arranged in said cylinder, and adapted to compress the air therein, and means for moving said plunger into the cylinder.

3. In combination with an oscillating puddling-furnace, a cylinder, a plunger in said cylinder adapted to compress the air therein, and a suitable flexible connection between the furnace and the plunger, substantially as and for the purposes described.

In testimony whereof, I affix my signature.

JAMES PETER ROE.
